(57) **CLAIM**

The ornamental design for a tread of an automobile tire, as
shown and described.

DESCRIPTION

FIG. 1 is a perspective view of a tread of an automobile tire showing my design;

FIG. 2 is a front view thereof;

FIG. 3 is a top view thereof;

FIG. 4 is a right side view thereof;

FIG. 5 is a fragmentary enlarged front view showing the
details of the tread portion thereof; and,FIG. 6 is a section view taken along line 6-6 in FIG. 5.
No claim is made to the unshaded portions of the tread of the
automobile tire.

The broken lines are used to show portions of the tire that are
not being claimed, and thus form no part of the claimed
design.
